UNITED STATES PATENT OFFICE.

STEPHEN WOOD McCALVE, JR., ROSCOE PARK McCALVE, AND BERNARD DUNCAN
McCALVE, OF CLIFFSIDE, NEW JERSEY.

SEWER BOAT.

Application filed February 9, 1925. Serial No. 7,761.

This invention relates to a sewer boat.

In the smaller municipalities the sewers are laid and supervised by engineers that in many cases are employed only temporarily by the municipality and their records being private records are not preserved by the municipality. In other cases the records are not properly looked after, become lost or are destroyed by fire. If a sewer has been laid and the maps and plans are not available it is impossible to determine where the Y outlets or connections are located. If a property owner desires to connect up with the sewer it is of prime importance that his connection be made to a Y since, if it is not done it is impossible to make a tight joint in the sewer pipe and sewer seepage results around where the sewer pipe has been cut out for the entering pipe. In order therefore not to cut the sewer pipe, excavation may be necessary for a considerable distance in order to locate the Y which entails unnecessary expense and where there is rock it entails a heavy charge upon the house builder.

One of the objects of this invention is to provide a device which will indicate the Y outlets of a sewer. Another object of this invention is to indicate the direction as well as the location of sewer outlets. Still another object of the invention is to enable the determination of any opening or break in a pipe.

Referring to the drawings:

Figure 1 is a plan view of a device embodying the principles of my invention being drawn through a sewer.

Figure 2 is a side view elevation of Figure 1.

Figure 3 is a plan view of a modified form of my invention.

Figure 4 is a diagrammatic view of the electrical wiring.

In carrying out our invention, I propose to provide a sled or boat 1 having runners or sides 2 and deck 3. Forward of mid-section I provide rotatable arms, 4, 4' and 4''. Said arms 4, 4' and 4'' have pivotal mountings 5, 5' and 5'' to deck 3. The arms 4, 4', being rotatable in the horizontal plane and arm 4'' in the vertical plane. Stops 6, 6' and 6'' limit the throw of the arms. Springs 7, 7' and 7'' are secured to deck 3 forward of the arms 4, 4', 4'' respectively, and also to the arms in order to rotate the arms forward, when pressure against the tips of the arms is

released, to bring contacts 8, 8' and 8'' carried at the base thereof into electrical contact with contact 9 secured to deck 3. Wires 10, 10' and 10'' are connected to contacts 8, 8' and 8'' and with wire 11 connected to contact 9, which are the four wires of a four stranded cable 12 and which pass down through opening 13 in deck 3 and are then secured to the stern of the boat from whence it extends. A tow rope 14 is secured to boat 1 in such a fashion as to pull the boat horizontally without lifting the prow and this is accomplished by passing a rope through openings 15, 15' in deck 3 on each side of the center line thereof to the underside of deck 70 3 and then through openings 16, 16' of the sides or runners and back through openings 17, 17' to the underside of the deck, said openings being adjacent the mid-section and thence to the rear where said tow rope is secured to the underside of the stern of the boat.

Cable 12 containing wires 10, 10', 10'' and 11 lead to bells 18, 18' and 18'' and to batteries 19 to form a circuit or circuits and to 80 ring the bell or bells when the contacts carried by the arms 4, 4', 4'' and 9 are closed.

The modified form of device is similar to the preferred embodiment except that the arms 4, 4', 4'' when rotated operate by means 85 of levers 19, 19', 19'', to sound mechanical bells 20, 20' and 20'' secured to deck 3.

The operation of the device is as follows: The tow rope 14 is passed down through the sewer in which it is desired to ascertain 90 where the Y connections are. The boat is then inserted in the sewer 21 and towed through the section which it is desired to be explored. The arms 4, 4', 4'' are held back from the contacts 8, 8', 8'' and 9 by the walls 95 of sewer 21, while the boat is towed. A Y connection being reached, the arm opposite the Y connection is swung back by the spring that is attached thereto causing its contact to complete the circuit and ring its particular 100 bell. As the bells are of different sizes and tonal qualities it can be immediately determined from the sound which arm or arms have located outlets or it may indicate breaks in the pipe line. Two bells ringing indicate 105 a Y connection or outlet; one bell ringing indicates a break.

Although the preferred embodiment is generally more satisfactory yet under certain conditions it may be desirable to dis- 110

pense with the electrical features. The sound of a bell can be heard for a very long distance when it is rung in a sewer pipe. The modified form is manipulated in the same manner, the only difference being that the arms themselves strike against a bell through a system of levers 19, 19', 19'', when they swing out as they come opposite to an opening in the pipe.

10 Of course modifications may be made in detail such as by making the arms extensible to adapt the boat to a large range of pipe diameters. Other variations may be made in the device and still fall within the scope and 15 principles of our invention and we do not desire to be limited to its use solely in connection with a sewer as the device is extremely useful to locate a break in any pipe of sufficient diameter to permit the device to be 20 used.

What we claim is:

1. An indicator comprising a body portion, said body portion consisting of a deck and side runners, arms pivotally mounted on said deck, one of said arms adapted to swing from 25 rear to front along the axis of the body portion and the other arms adapted to swing from rear to front and laterally of said body portion, means to indicate when any of said arms have swung beyond a predetermined point in its arc of rotation.

2. A pipe indicator comprising a body portion consisting of a deck and side runners, rotatable arms pivotally mounted on said 35 deck, means to maintain the tips of said arms in frictional engagement with the wall of the pipe, a bell for each arm and means to actuate the bell when any of said arms rotates beyond a certain predetermined point in its 40 arc of rotation.

3. A pipe indicator comprising a body portion consisting of a deck and side runners, arms pivotally mounted on said deck, springs secured to said arms and to said deck forward of said arms to maintain the free 45 ends of said arms in frictional contact with the wall of the pipe when said indicator has been inserted in the pipe with the arms rotated against the tension of the springs from front to rear, individual bells for each arm 50 and means to actuate each bell when its arm is rotated beyond a predetermined point in its arc of rotation from rear to front.

4. A pipe indicator comprising a body portion consisting of a deck and side runners, an arm pivotally mounted on said deck and adapted to swing from rear to front along the longitudinal axis of said deck, arms pivotally mounted on said deck on each side of 55 said central arm and adapted to swing from 60 rear to front of said deck portion and side- 65 wise thereof, springs secured to said arms and to said deck to maintain the free ends of said arms in frictional contact with the interior of the pipe wall, individual bells for 70 each of said arms, a contact member carried by said deck, contacts at the pivoted ends of said arms to engage said contact member carried by the deck when any of said arms has moved beyond a certain pre- 75 determined point in its arc of rotation from rear to front, wires connecting said contacts with the said individual bells and a source of electrical supply.

Signed at Cliffside, in the county of Bergen and State of New Jersey January, A. D. 1925.
